UNITED STATES PATENT OFFICE.

JOSEPH G. CROSS AND MARK G. ALNESS, OF EVERETT, WASHINGTON.

DESIGN FOR A PRIMING-CUP.

51,224.

Specification for Design.

Patented Sept. 4, 1917.

Application filed January 4, 1917. Serial No. 140,643. Term of patent 7 years.

To all whom it may concern:

Be it known that we, JOSEPH G. CROSS and MARK G. ALNESS, citizens of the United States, and residents of Everett, in the county of Snohomish and State of Washington, have invented a new, original, and ornamental Design for Priming-Cups, of which the following is a specification, reference being had to accompanying drawing, forming a part thereof.

In the drawing the figure illustrates a side elevation of a priming cup showing our new design.

We claim:

The design for a priming cup as shown.

JOSEPH G. CROSS.
MARK G. ALNESS.
